FRANK PARDEE AND FRANK PARDEE, JR., OF HAZLETON, PENNSYLVANIA, ASSIGNEES
TO ANTHRACITE SEPARATOR COMPANY, OF HAZLETON, PENNSYLVANIA, A COR-
PORATION OF PENNSYLVANIA

CAR-LOADING CHUTE

Application filed July 25, 1929. Serial No. 380,802.

This invention relates to improvements in loading chutes which while not limited thereto is particularly adapted for transferring coal from bins of a coal breaker to a standard railway coal car.

In the handling of coal it is important that the breakage be minimized because the so called fines or extremely small pieces have little or no sale value. Heretofore it has been the common practice to transfer coal from the breaker bin to freight cars by means of a simple inclined chute which usually remains at a fixed angle. This results in discharging the load in such a manner that considerable breakage occurs.

Our improved car loading chute provides means for varying the angle of inclination of the flowing stream of coal, so that as the pile accumulates in the car the angle of flow can be varied to reduce the turbulent action during the loading. Means are also provided for retarding the coal flow when the chute is positioned at a relatively steep angle and means are also provided whereby the retarding means can be either automatically or manually caused to move to an inoperative position when the chute is inclined at a relatively gentler angle.

Our invention will be fully apparent from the following specification when read in connection with the accompanying drawings and will be defined with particularity in the appended claims.

Referring in detail to the drawings:

Fig. 1 is a plan view illustrating a bin equipped with our improved car loading chute, the view also showing a railway car adapted to receive material from the bin;

Fig. 2 is a side elevation of the parts shown in Fig. 1;

Fig. 3 is a section on line 3—3 of Fig. 1;

Fig. 4 is an enlarged detail section on line 4—4 of Fig. 1;

Fig. 5 is a horizontal section on line 5—5 of Fig. 4;

Fig. 6 is a transverse section on line 6—6 of Fig. 4;

Fig. 7 is a similar transverse section showing the retarding member in non-retarding position;

Fig. 8 is a fragmentary plan view of a central portion of the discharge chute;

Fig. 9 is a sectional view illustrating a modified detail of means for releasably holding the retarding member in working position;

Fig. 10 is a side elevation of one end of the discharge chute of Fig. 9 illustrating a mounting for the latch members;

Fig. 11 is a side elevation of a modification;

Fig. 12 is a cross section on line 12—12 of Fig. 11;

Fig. 13 is a section on line 13—13 of Fig. 11.

Referring in detail to the drawings, 10 represents a bin receiving coal from the breaker. The lower end of the bin is formed with an outlet neck portion 12 which is perforated as shown at 14 for the discharge of extremely fine particles as well as dust accumulations. The dust and fines are adapted to be rejected through a chute 16 leading to a waste pile.

Our improved car loading chute indicated as a whole by numeral 18 is swiveled or pivoted relatively to the neck portion 12 of the bin. The neck portion of the bin makes a quarter turn as shown at 20 in Figs. 1 to 3. At the end of the neck there is a rod 22 carried in brackets 24 and forming a pivotal or hinged support for the chute 18.

The chute 18 is substantially rectangular in cross section and is of hollow form as shown in Fig. 6.

Located within the chute we provide a retarding member indicated as a whole at 28, this member being formed of a top wall 30 and downwardly extending side walls 32—32. These side walls, as shown clearly in Fig. 5, are of undulating or zig-zag form. The height of the side walls 32 of the retarding member is appreciably less than the height of the side walls 34—34 of the chute 18.

Suitable guide strips 36—36 may be riveted, welded, cast or otherwise secured near the upper end of the chute. Similar guide strips 38—38 are suitably secured near the lower end of the chute. These are merely retaining guides and make a very loose sliding fit with the ends of the retarding member.

Inasmuch as the chute is inclined to the horizontal the guide strips 38-38 prevent the retarding member from sliding endwise.

When the chute is in its relatively steep inclined position as illustrated in full lines in Figs. 1 and 2, it is supported in part by a cable 40 having a ball 42 or other enlargement secured thereto. The cable 40 passes through an opening which is relatively narrow, as indicated at 44 and provided with an enlargement 46, of a size sufficient to permit the ball 42 to pass therethrough at certain times as hereinafter more fully explained. The lower extremity of the cable 40 is secured to an ear 48 formed on the retarding member.

The cable 40 passes over sheaves 50, carried by a suitable fixed support 52.

So long as the ball 42 lies below the narrow slot 44, a pull on the free end 54 of the cable 20 will move both the chute and the retarding member 28 about the rod 22 as a pivot.

When the chute is in the steep angular positions it is desirable to have the retarding member in the operative position illustrated 25 in Figs. 4 and 6. This will tend to retard the rapid flow of coal so as to minimize breakage of the lumps which will naturally fall from the end of the chute at a relatively slow speed. However, when the chute is inclined 30 at a more gentle angle, for example, when swung to dotted position of Figs. 2 and 4 the retarding action is undesirable. In this position the retarding member may be automatically lifted out of the way to the position, for 35 example, as illustrated in Fig. 7. This may be accomplished automatically as hereinafter described by the ball 42 slipping from under the narrow portion 44 of the opening 46 to the enlarged portion, where it is free to pass 40 through the opening. Of course when the ball is free to slip through the hole 46 a relative movement between the chute and the retarding member will take place.

The arrangement as described below is so 45 designed that the ball 42 will slip through the opening when the chute reaches a predetermined angular position. Or, if desired, the narrow slot 44 may be of such length that the ball will not slip through without movement being forcibly imparted to the cable 40 in a direction toward the enlarged opening 46. This relative movement may be effected 50 by the workman striking a blow on the cable. For example, it may be hit with a shovel or 55 with a club. Usually there will be a workman in the car assisting in trimming the pile and when he observes that the coal is flowing at too slow a rate because of the retarding member it is merely necessary that he strike 60 the cable so as to permit the retarding member to move to inoperative position. It is of course understood that the weight of the chute will effect a relative movement between it and the retarding member whenever the ball 42 65 slips through the enlarged hole 46.

For automatically causing the ball 42 to slip through the enlarged hole 46 and thus cause the retarding member to move to inoperative position when the chute attains a gentle angle, we provide a bail-like member 56 pivoted at 57 to a fixed support as shown in Fig. 4. The bridge portion 58 of this bail-like member normally bears freely against the cable 40 when the chute is in the steep inclined position. When the chute is lifted to a gentler angle the bridge portion 58 pushes the cable 40 to the left in Fig. 4 and when the chute reaches a predetermined position dotted in Fig. 4 the ball 42 will slip through the slot. Thus the retarding member will be lifted relatively to the chute and the coal can flow freely.

In a modified arrangement instead of depending on the ball or other devices carried by the cable for holding the retarding member in its operative position at certain times and permitting its movement to non-operative position at other times, the chute is provided with a plurality of latches 60 pivoted at 62 on brackets 64 secured near the ends of 65 the chute. Springs 66 surrounding the pivot studs 68 on which the latches are mounted tend to press the latches inwardly to the position of Fig. 9 where their teeth 70 overlap the top surface of the retarding member. If 70 desired, indentations 72 and 74 may be formed in the retarding member for coaction with the teeth 70 as shown.

With the arrangement of Figs. 9 and 10 it is clear that the latches may occupy the 100 position of Fig. 9 when the chute is inclined at a steep angle. Thus the retarding member will be operative to impede the travel of coal flowing through the chute so as to prevent breakage which might be occasioned by 105 too rapid a flow. On the other hand, when the chute is moved to the more gentle angle the latches can be released and thus the retarding member will be moved to its non-operative position.

Referring to Figs. 11 to 13 inclusive, we have shown a modification in which a retarding member 80 is adapted to be moved in a direction at right angles to a chute 82 through a longitudinal slot 84, which is of zig-zag or serpentine form following the shape of retarding member 80. In this embodiment of the invention the retarding member is supported on a longitudinally extending bar 86, which at its ends is secured to cross pieces 88. The cross pieces 88 are secured to bars 90, which are slidable in bearings 92 carried by the side walls of the chute 82. The bars 90 at their ends are connected by tie bars 94. The several bars 90, 94 and 86 forming sort of a skeleton framework for supporting the retarding member 80, and this hollow framework is slidable relatively to the chute 82. Cables 96 are connected with the upper end 110 of the framework and attached to a single ca- 115

ble 98, which passes over a sheave 100. By manipulating the free end of the cable 98 the position of the retarding member 80 relatively to the chute may be varied as will be understood. A certain amount of relative change between the retarding member and the chute will also take place when supporting cable 102 for the outer end of the chute 82 is adjusted. In practice the cables 102 and 98 may be actuated by suitable winches or they may be moved by a straight pull exerted by workmen. It will be understood that when the retarding member is lifted to its highest position with relation to the chute that the maximum retarding action is secured. By lowering the retarding member the retarding action may be varied and when the member 80 is in its lowest position it will exert practically no retarding action and in the extreme position the upper end of the retarding member will lie practically flush with the bottom surface of the chute 82. This retarding member 80 may be moved to various intermediate positions by manipulating the cable 98 as will be understood.

While we have described quite specifically the details of the embodiments of the invention herein illustrated it is not to be construed that we are limited thereto since various modifications and substitutions of equivalents may be made by those skilled in the art without departure from the invention as defined in the appended claims.

We claim:

- 25 1. In combination with a bin, a chute movable to different angular positions, a transversely shiftable upright retarding member in said chute and means for supporting said member in retarding position when the chute is inclined at a relatively steep angle and in non-retarding position when the chute is inclined at a gentle angle.
2. In combination with a bin, a chute mounted for movement relatively thereto, and a transversely shiftable member normally in position to retard flow of material through the chute when the same is inclined at a relatively steep angle, and means for supporting said member in a non-retarding position.
3. A chute for handling material such as coal, means for supporting said chute at different angles of inclination, a member slid-able to different positions within the chute effective to retard the flow of said material when the chute is inclined at a relatively steep angle, and means for supporting said member in non-retarding position when said chute is inclined at a relatively gentle angle.
4. In combination with a chute mounted for movement to different angular positions, a retarding member extending longitudinally of the chute and mounted within the chute for slid-able up and down movement relatively thereto and means for automatically shifting the retarding member relatively to the chute

upon movement of the chute to a predetermined angular position.

5. A chute having one end loosely journaled on a fixed member, a retarding member within the chute, a cable secured to the retarding member and passing through an aperture formed in the chute, and an enlargement formed on said cable, said enlargement being adapted to coact with the wall of the chute adjacent the aperture so as to support the chute when inclined in one predetermined position, said enlargement being adapted to slip through said aperture when the chute is moved to another predetermined angular position so as to move the retarding member relatively to the chute.

6. A chute of tubular cross section, a substantially U-shaped member located therein having at least one wall of zig-zag form in plan adapted to retard the movement of material through the chute and means whereby said U-shaped member is automatically moved relatively to the chute to non-retarding position upon movement of the chute to a predetermined angular position.

7. A chute of the character described, means for supporting the chute in a plurality of different inclined positions, a retarding member having at least one upright wall of zig-zag form said member being adapted to normally retard the flow of material through the chute and means for holding said member in an elevated non-retarding position.

8. A chute of the character described, means for supporting the chute in a plurality of different inclined positions, a retarding member having at least one upright continuous wall of zig-zag form said member being adapted to normally retard the flow of material through the chute and means whereby said retarding member is automatically shifted to a non-retarding position when the chute is moved to a predetermined angular position.

In witness whereof, we have hereunto signed our names.

FRANK PARDEE.
